UNITED STATES PATENT OFFICE.

HARMON DE LEON MOISE, OF SUMTER, SOUTH CAROLINA, ASSIGNOR, BY DIRECT AND MESNE ASSIGNMENTS, TO SUMTER SUPER-SIPHON COMPANY, OF SUMTER, SOUTH CAROLINA.

AUTOMATIC FLUSHING APPARATUS.

Application filed October 24, 1921. Serial No. 510,023.

To all whom it may concern:

Be it known that I, HARMON D. MOISE, a citizen of the United States, residing at Sumter, in the county of Sumter, State of 5 South Carolina, have invented certain new and useful Improvements in Automatic Flushing Apparatus, of which the following is a description, reference being had to the accompanying drawing and to the figures of 10 reference marked thereon.

The invention relates to new and useful improvements in an automatic flushing apparatus, and more particularly a flushing apparatus of the type used for periodically 15 flushing sewers or the like.

An object of the invention is to provide a flushing apparatus of the above type which can be placed in the usual tank designed for the manual flushing of sewers and 20 substituted for the manually controlled flushing devices contained therein.

A further object of the invention is to provide an automatic flushing device of the siphoning type which can be placed wholly 25 within the flushing tank, the bottom of which is substantially on the same level of the bottom of the sewer pipe to which said tank is connected.

A still further object of the invention is to 30 provide an automatic flushing apparatus of the siphoning type wherein air confined in the air chamber of the siphon is caused to escape for starting the siphonic action and the flow of the flushing water through a blow-off pipe independent of the flushing 35 pipe connections.

Another object of the invention is to provide a flushing apparatus of the above type wherein the blow-off pipe is connected to the 40 sewer pipe and so constructed that it may be reshaped or adjusted to vary the sustained column of water necessary to start a siphonic action.

Another object of the invention is to provide an automatic siphon flushing apparatus 45 having an intake pipe connected to an outlet pipe which is in turn connected to a sewer pipe, with a combined water and air inlet pipe discharging into the siphon and an air escape pipe connected to the siphon and disposed so that the water may rise in the 50 siphon intake pipe to a point below the point where the intake pipe connects with or dis-

charges into the outlet pipe before the air 55 in the siphon is confined.

Still another object of the invention is to provide an automatic siphon flushing apparatus for a sewer pipe which is connected to the sewer pipe by a pipe so disposed relative to the longitudinal center line of the 60 sewer pipe as to leave the end of the sewer pipe free from obstruction whereby access thereto may be readily had.

These and other objects will in part be obvious and will in part be hereinafter more 65 fully disclosed.

In the drawings:—

Figure 1 is a view, partly in vertical section and partly in perspective, of an automatic siphon flushing apparatus embodying 70 my improvements;

Fig. 2 is a horizontal sectional view through a portion of the tank and through the siphon flushing apparatus;

Fig. 3 is a view in vertical section through 75 a tank and at one side of the siphoning apparatus, showing a slightly modified form of apparatus, certain of the parts being broken away to show the arrangement of the air escape pipe and the combined water and 80 air intake pipe;

Fig. 4 is a view showing, more or less 85 diagrammatically and in plan, the arrangement of the pipes in the modified form of the invention; and

Fig. 5 is a detail of the air entraining connection.

The invention in its broadest aspect includes a flushing tank for a sewer or the like which is connected to the sewer by a 90 pipe or pipes shaped to deliver the water from the tank to the sewer by siphonic action. The siphon intake pipe immediately receiving the water from the flushing tank opens downwardly, and its open end is preferably disposed a short distance from the bottom of the flushing tank so that a large proportion of the water in the flushing tank will be siphoned into the sewer. The flushing tank is filled by a supply pipe which 100 discharges directly into the siphon, and since the supply pipe is constructed so that the inflowing water entrains air and carries the same into the siphon, the air escape pipe is connected to the siphon and is so disposed that the water may rise in the 105

siphon intake pipe to a point slightly below the point where the siphon intake pipe discharges into the siphon outlet pipe connected to the sewer before the air in the siphon is 5 confined, and air continues to escape from said pipe as the water accumulates in the flushing tank until a level is reached which starts the siphonic action.

A blow-off pipe is provided which is independent of the pipe connections of the siphon to the sewer. This blow-off pipe is preferably discharged into the sewer and is so shaped as to sustain the desired column of water before flushing takes place. By 10 reshaping or bending the pipe, the height of the sustained column of water may be varied. The siphon pipes are connected to the sewer pipe by means of a T-shaped pipe extending at an angle to the longitudinal center 15 of the sewer pipe which leaves the end of the sewer pipe free and open to give ready access to the same for lighting and cleaning. The siphon connections to the sewer pipe are so arranged as to be fully above the bottom 20 line of the sewer pipe so that they may be readily substituted for the ordinary mechanical devices heretofore used in flushing sewers without altering or reconstructing the flushing tank masonry.

30 Referring more in detail to the drawings, my improved flushing apparatus consists of a flushing tank 1 which may be of any desired construction. Leading into the flushing tank is a sewer pipe 2 which connects to 35 the tank near the bottom thereof. Connected to the end of the sewer pipe is a T pipe 3, and connected to said T pipe 3 is a U pipe 4 which in turn is connected to a U pipe 5. These pipes are connected in the usual way 40 and are so disposed as to be located to one side of the center line of the sewer pipe so that the end of the sewer pipe may be closed by a cover 6 which can be readily removed to permit the lighting of the sewer pipe and 45 to give ready access thereto.

Connected to the pipe 5 is the outlet pipe 7 of the siphon. In the form of my invention as shown in Fig. 1, there is an intake pipe 8 which entirely surrounds the pipe 7 and which is usually referred to in the art 50 as a bell. The intake pipe 8 is supported by the pipe 7. This is accomplished by providing fins 8^a which are formed as a part of the pipe 8. These fins are notched out at 8^b so as 55 to engage and seat on the end of the pipe 7. The fins also hold the pipe 8 concentric to the pipe 7. The fins are very thin so as to permit the free flow of the water during 60 flushing. These pipes are arranged so as to form a siphon, and the pipe 8 becomes an intake pipe of the siphon, while the pipe 7 becomes the outlet pipe of the siphon. These pipes are connected so that flushing water flowing through the pipe 8 will pass over 65 into the pipe 7. The upper end of the pipe

7 is adjacent the upper end of the pipe 8, and the pipe 8 has its open end near the bottom of the tank so that the flushing water in the tank will to a large degree be siphoned from the tank. The U pipe 5 rests on the 70 bottom of the tank 1, and a support of cement 3^a or other suitable material is placed under the T pipe 3. This makes a very durable support for the siphon and enables it to be readily inserted in a flushing tank without breaking into the structure of the tank to 75 install the same.

Connected to the siphon is an air escape pipe 9, its upper end above the flushing height of the water. Said air escape pipe 9 80 extends down through the top of the bell or intake pipe 8 of the siphon, and the lower end 10 of this pipe terminates slightly below the upper end 11 of the pipe 7. Said pipe 9 is open at both its upper and lower ends. 85

Arranged preferably in the air escape pipe, but free therefrom, is a water inlet pipe 12. Said pipe 12 is considerably smaller in diameter than the inner diameter of said pipe 9 so that there is a free air space 90 around the pipe 12 through which air may escape from the siphon. Water is supplied to the pipe 12 from a supply pipe 13 controlled by a suitable valve 14. In this pipe 12 is an air injection connection 15 which is provided with an opening 16 to the atmosphere and a jet pipe 17 extends slightly beyond said opening to the atmosphere (see Fig. 5). As water passes through the jet, air will be drawn in through the opening 16 and entrained with the water and carried with the water into the siphon. This water inlet pipe is preferably bent laterally at its lower end, as indicated at 18, so that the air carried in with the water will pass into the upper part of the bell 8 rather than escape directly through the pipe 9. 95

A blow-off pipe 19 is connected at 20 with the outlet pipe 7 and is connected at 21 with the U-pipe 4. Said connection 21 is made at the lower side of the U-shaped pipe to said connection extending up into the U-shaped pipe a slight distance above the water seal in the siphon. Assuming that the tank has just been flushed and the water has settled to normal condition, there will be a water seal in the siphon pipes 4, 5 and 7 to the line X—X, and the blow-off pipe 19 also. This blow-off pipe 19 has its outlet end extending slightly above this line X—X. 100

As water with air entrained therein is delivered to the bell 8, the bell and flushing tank will be filled with water. As the tank and bell are filled with water, air in the bell escapes through the pipe 9 and the water level both in the bell and flushing tank will be the same and they will rise together until the line Y—Y is reached, when the lower end of the pipe 9 will be closed. As the water continues to pass into the bell, 105 115 120 125 130

it will rise slightly above the lower end of the pipe 9 and the air in the upper end of the bell and the upper portion of the pipe 7 being confined will force the water level in the bell down to the end of the pipe 9 and some of the air will escape through the pipe 9. The water still continues to rise in the tank outside of the bell, but the level in the bell will be maintained at the lower end of the pipe 9 and air will continue to escape through this pipe 9.

When the water in the tank reaches the point Z—Z, then the water column from Y to Z is of the same height as the column of water in the pipe 19, that is the column of water from the lower extreme invert point of the pipe 19 to the upper end of the outlet end 21. The pressure of the water, therefore, in the flushing tank through the confined air in the siphon operating upon the blow-off pipe to cause the air and water in the blow-off pipe to pass out through the outlet 21 and the air in the siphon will then follow out through the blow-off pipe and the water will then rise in the bell 8 and flow over into the pipe 7 and the siphonic action will thus be started. The water will continue to flow from the flushing tank, flushing the sewer, carrying all air out of the siphon until the level of the water reaches the lower end of the bell 8 so that air is drawn in underneath the lower end of the bell 8 and the siphon broken.

During the passing of the water from the tank through the bell into the outlet pipe 7, the water is flowing against the air escape pipe 9 and in a direction opposed to said open end of the pipe. This effectively seals the pipe 9 and prevents air from entering through said pipe 9 to break the siphon. As soon as the siphon is broken, then the water in the bell 8 will sink below the lower end of the pipe 9 and air will enter freely through the pipe 9 so that the water in the flushing tank and in the bell 8 will find a common level which is slightly above the lower end of the bell 8. All the water in the pipe 7 will fall seeking its level in the bottom of the siphon, up to the line X—X, resealing the siphon and the blow-off pipe 19.

It will be readily seen that by reshaping or bending the blow-off pipe 19, the column of water in the blow-off pipe between the lower extreme point thereof and the upper end of the outlet pipe 21 may be decreased and thus the height of the sustained column in the flushing tank varied. The end of the blow-off pipe 19 extends slightly above the overflow point in the U-shaped pipe 4 so as to prevent water in the seal from rushing back into the blow-off pipe and thus preventing the proper starting of the siphon. Attention is called to the fact that the water seal in the main siphon is deeper vertically

than the seal in the pipe 19, and this prevents the entrapped air from escaping through the siphon pipes 7, 5 and 4, (see Fig. 1).

It will be understood, of course, that during the flushing action and immediately after, water will pass into the blow-off pipe and seal the same for the next siphonic action of the flushing apparatus. Attention is called particularly to the fact that the pipes 4, 5, 7 and 8 are all located above the lower or bottom side of the sewer pipe 2 and above the bottom of the flushing tank 1. Therefore, my improved siphonic flushing apparatus may be readily substituted for the ordinary manually controlled flushing devices now in existence and without changing the construction of the flushing tank.

In Fig. 3 I have shown a slightly modified form of flushing apparatus in that the intake pipe of the siphon, instead of being in the form of a bell surrounding the outlet pipe to the siphon, is located at one side thereof. In said figure, the sewer pipe is indicated at 2, and said pipe is provided with a T-pipe connection 3, a U-pipe 4 and a U-pipe 5 which are connected to the upright outlet pipe 7^a. Said outlet pipe 7^a at its upper end is provided with a U-pipe 22 which supports an intake pipe 23. It will be noted that these pipes are arranged in rectangular form, as viewed from above. In other words, the pipe 4 lies substantially at right angles to the center of the sewer pipe 2, the pipe 5 is in a plane at right angles to the plane of the pipe 4, and the pipe 22 is in a plane at right angles to the pipe 5 and also in a plane substantially parallel with the plane of the pipe 4. The lower end 24 of the pipe 23 is slightly above the sewer pipe 2 so that the cover 6 may be readily removed so as to give access to the sewer pipe. The U-pipe 5 rests on the bottom of the tank, while a support 3^a is built up for the T-pipe 3, as above described in connection with the form of apparatus shown in Fig. 1. I also provide a standard 23^a which is attached to the end of the pipe 23 and rests on the bottom of the tank. This forms a very durable support for the entire siphon and permits its ready installation without in any way disturbing the structure of the tank.

An air escape pipe 25 is connected to the U-pipe 22 at the lower portion thereof. Said air escape pipe extends downwardly from said U-pipe 22 a slight distance. Water with air entrained therein is delivered to the siphon through the pipe 26 which is in construction similar to the pipe 12 and the lower part thereof only has been shown. It will be noted that the water inlet pipe is separated from the air escape pipe in this form of the invention, and as a matter of fact it may be made separate from the air

escape pipe in the bell type of siphon shown in Fig. 1. I have shown it passing through the air pipe 9 merely for the sake of convenience; its arrangement in the air escape pipe has no function.

The operation of the siphoning apparatus shown in Fig. 3 is the same as that shown in Fig. 1, except for the fact that the air escape pipe is closed by the water in the flushing tank outside of the siphon. Air escapes freely from the siphon until the water in the flushing tank reaches the level X—X, when the end of the air escape pipe is covered. The air in the siphon is now confined. Air and water continue to pass into the siphon, and as the air pressure increases the air will be forced out through the air escape pipe and the water level in the intake pipe 23 of the siphon will be maintained substantially on the line X—X, that is, on a line containing the end of the air escape pipe. The air bubbles up through the accumulating water in the flushing tank and escapes. When the column in the flushing tank reaches a sufficient height so as to overcome the column of water in the blow-off pipe, then the air will be forced through the blow-off pipe and will escape from the siphon and the siphonic action will start.

While I have shown my improved siphoning apparatus as made up of pipe sections and so described my preferred form of structure, it will be understood that these pipes may be cast in longer sections. It will also be understood that the pipe sections may be set at any desired angle to each other, as viewed from above, so as to best adapt themselves to the shaping of the tank in which they are placed. So far as the feature of placing the siphon in a tank without breaking into its structure is concerned, it will be understood that I do not desire to be limited to the delivering of the water with entrained air into the bell or siphon directly. It may be otherwise supplied to the tank and, if delivered outside of the siphon, of course no air need be entrained therein, the pipe 9, Fig. 1, being lengthened downwardly far enough to entrap enough air after each flush, likewise the pipe 25, Fig. 3.

It is obvious that other changes in the details of construction and arrangement of parts may be made than those shown in the drawings without departing from the spirit of the invention as set forth in the appended claims.

Having thus described the invention, what I claim as new, is:

1. The combination of a flush tank, a

liquid conductor thereinto, a sewer pipe extending into said tank, and an automatic siphoning apparatus located wholly within said tank and connected to said sewer pipe for periodically discharging the flushing water in said tank into said sewer, said siphoning apparatus including pipes located laterally at an angle to the longitudinal center of the sewer pipe and arranged so as to permit free access to said sewer pipe.

2. A flushing apparatus including in combination, a tank, a sewer pipe extending into the tank, a T-pipe on the end of the sewer pipe, a U-pipe connected to the T-pipe and extending at an angle to the sewer pipe, a second U-pipe connected to the last-named U-pipe and arranged to form a water seal, a siphon having an outlet pipe connected to the U-pipe forming the water seal, an intake bell surrounding the outlet pipe and closed at its upper end, an air pipe extending from above the high water line through the upper end of the bell and down into said bell to a point below the upper end of the outlet pipe, a water inlet pipe extending down through the air pipe but spaced from the side walls thereof so as not to prevent the air from freely passing through the air pipe.

3. A flushing apparatus including in combination, a tank, a sewer pipe extending into the tank, a T-pipe on the end of the sewer pipe having a removable closure to give ready access to the sewer, a U-pipe connected to the T-pipe and extending at an angle to the sewer pipe, a second U-pipe connected to the last-named U-pipe and arranged to form a water seal, a siphon having an outlet pipe connected to the U-pipe forming the water seal, an intake bell surrounding the outlet pipe and closed at its upper end, an air pipe extending from above the high water line down through the upper end of the bell and down into said bell to a point below the upper end of the outlet pipe, a water inlet pipe extending down through the air pipe but spaced from the side walls thereof so as to permit the air to freely pass through the air pipe, a blow-off pipe connected with the outlet pipe adjacent the upper end of the U-shaped sealing pipe and connected with the U-shaped pipe leading from the sealing pipe to the sewer at the overflow point thereof, said blow-off pipe extending into said U-shaped pipe to a slight distance above the lower surface thereof.

In testimony whereof, I affix my signature.

HARMON DE LEON MOISE.
